UNITED STATES PATENT OFFICE.

GEORGE WILLIAM ALDRICH, OF ANTIGO, WISCONSIN.

WASHING-MACHINE CYLINDER.

1,256,635.

Specification of Letters Patent.

Patented Feb. 19, 1918.

Application filed October 4, 1915. Serial No. 54,062.

To all whom it may concern:

Be it known that I, GEORGE WILLIAM ALDRICH, a citizen of the United States, residing at Antigo, in the county of Langlade and 5 the State of Wisconsin, have invented a new and useful Washing-Machine Cylinder to be Used for Dry-Cleaning, Washing, and Carpet-Cleaning Machines, of which the following is a specification.

10 My present invention relates to new and useful improvements in washing machines more particularly of the type embodied in my co-pending application for patent filed Oct. 4, 1915, Serial No. 54,063.

15 It is in general the object of my present invention to embody the general advantages of the structure of my aforementioned application in a wooden cylinder.

A more specific object resides in the provision of an arrangement wherein the various stave and rib portions of the cylinder may be readily replaced upon becoming worn, to thus procure an indefinite length of 20 life of the cylinder, and it is a further object in this connection to provide an arrangement wherein the rib members of the cylinder may be reversed upon becoming worn.

25 A still further object of the invention resides in the provision of novel means for introducing cleansing fluid into the cylinder, whereby said cleansing fluid serves as a lubricating medium for the clothes in their rubbing engagement with the ribs.

With the above and other objects and 30 advantages in view the invention resides more particularly in the novel combination formation and arrangement of parts herein-after described and pointed out in the accompanying claim.

40 In the drawings:

Figure 1 is a perspective view of a wooden stave cylinder constructed in accordance with my present invention.

45 Figs. 2, 3 and 4 are partly diagrammatic transverse sectional views through the cylinder showing the successive lifting, dropping, and rubbing actuation of a mass of clothes therein.

Fig. 5 is an end view of the cylinder.

50 Fig. 6 is an elevational view of one of the end rubbing plates of the cylinder.

Fig. 7 is a transverse sectional view there-through on the line 7—7 of Fig. 6.

Fig. 8 is an elevational view of one of the 55 end head plates of the cylinder.

Fig. 9 is a detail view of one of the latch members of the door.

Referring now more particularly to the accompanying drawings, the peripheral portion of the cylinder comprises a series of 60 wooden staves 20, certain of the staves being spaced apart for the disposition there-between of a series of rubbing rib boards 21 and a single relatively large lifting rib board 22, the spaces between the rubbing 65 ribs being considerably less than the spaces between the lifting rib and adjacent rubbing rib whereby to procure squeezing pockets as in my said co-pending application. The washing operation procured by the pres- 70 ent cylinder being similar to the operation procured in my said application with the exception that the ribs are not slanted and hence do not procure a positive lon- 75 gitudinal movement of the mass of clothes in the cylinder. The staves and rib boards are bolted or otherwise secured at their ends to the peripheral portions of end 80 head plates 23, with the exception of a cer- 85 tain number of staves at one side of the lift- 80 ing rib board 22 which are secured to door straps 24 hinged to the connected body of staves to form a door, the outer portion of this door comprising a relatively wide and heavy stave 25 in which is set at its ends a 85 pair of spring urged locking plungers 26 adapted to engage in socket members 27 car- 90 ried by retaining bands 28 disposed about and secured to the ends of the main body of staves and rib boards.

The end portions of the rubbing rib boards 21 and lifting rib board 22 engage in cut away peripheral portions 29 and 30 respectively of the end head plates and said rib board end portions are also disposed in 95 similar cut away portions 30 and 31 re- 95 spectively of a pair of end rubbing plates 32 which are fitted in the ends of the cylinder against the head plates 23, these end rubbing plates being provided with series of 100 inwardly struck radial rubbing ribs 33. Bolted to the head plates 23 are pintle hubs

34 whereby the entire cylinder may be journally mounted.

To set up an agitation of cleansing fluid in an outer drum in which the cylinder is 5 adapted to be disposed the staves 20 are provided with longitudinal relatively wide grooves 35 in their outer faces, the walls of said grooves being oppositely and inwardly inclined and for scooping cleansing fluid 10 into the cylinder to lubricate the clothes upon their engagement with the rubbing ribs, oppositely inclined longitudinal series 15 of passages 36 communicating with the longitudinal grooves are formed in the staves whereby cleansing fluid is scooped into the cylinder upon rotation of the cylinder in either direction.

By the foregoing description it is seen that a cylinder has been provided which is 20 of maximum simplicity and which may be readily assembled and disassembled to permit the substitution of fresh staves or rib boards upon wear. Also it is noted that both edge portions of each rib board are

rounded and thus said rib boards may be 25 reversed upon wear occurring at the exposed edge portions thereof.

What is claimed is:

A cleaning cylinder comprising a peripheral wall formed of staves having a series of 30 oppositely inclined perforations extending therethrough, spaced rubbing ribs and a lifting rib, close fitting joints being provided between the peripheral edges of said staves, rubbing ribs and lifting rib and said staves having their inner faces smooth and unbroken and being provided in their outer surfaces with central longitudinally extending grooves, the walls of said grooves being 35 oppositely and inwardly inclined, said inclined perforations communicating with the said central longitudinally extending grooves, and end wall members closing the 40 ends of the cylinder.

GEORGE WILLIAM ALDRICH.
